STOCKING

Leland A. Fillmore, Harriman, Tenn., assignor to Burlington Industries, Inc., Greensboro, N.C., a corporation of Delaware

Filed Mar. 17, 1965, Ser. No. 84,335

Term of patent 14 years

(Cl. D47—7)

FIG. 1 is a schematic view of the stocking; and FIG. 2 is a scale size fragmentary plan view of the fabric that extends from the welt to the toe forming the body of the stocking of my new design.

The welt and toe portions of the stocking are conventional.

I claim:

The ornamental design for a stocking, as shown and described.
